UNITED STATES PATENT OFFICE.

EARNEST P. WELCH, OF GARY, INDIANA.

AUTOMATIC CUT-OFF AND REVERSE FOR STEAM-ENGINES.

1,358,403.

Specification of Letters Patent. Patented Nov. 9, 1920.

Application filed December 24, 1918. Serial No. 268,179.

To all whom it may concern:

Be it known that I, EARNEST P. WELCH, a citizen of the United States, residing at Gary, in the county of Lake and State of Indiana, have invented certain new and useful Improvements in Automatic Cut-Offs and Reverses for Steam-Engines, of which the following is a specification.

This invention relates to steam engine 10 valve gear and more particularly to an improved automatic cut-off and reverse for steam traction engines.

One object of the present invention is to provide, in steam engine valve gear, an automatic means for controlling the motion of the automatic cut-off valve with relation to the main valve, and manually controlled steam actuated means for reversing the eccentrics which constitute a part of the means 20 for controlling the motion of the main and automatic cut-off valves.

A further object of the invention is to provide valve gear of the class described which will prove more efficient than manually controlled mechanically operated reverse mechanisms heretofore employed and by which economy in fuel and the consumption of water will be effected and the weight of the engine and valve gear considerably 30 reduced.

In the accompanying drawings:

Figure 1 is a view in side elevation of the valve gear embodying the present invention installed upon a traction engine; 35 Fig. 2 is a plan view of the valve gear, the valve chest of the engine being shown in horizontal section;

Figs. 3 and 3^a represent a horizontal sectional view through the manually controlled 40 steam operated means for reversing the eccentrics comprising a part of the means for controlling the movement of the main and automatic reverse valves;

Fig. 4 is a vertical sectional view on the 45 line 4—4 of Fig. 3^a looking in the direction indicated by the arrows and showing the rotatable member of the servo-motor in its intermediate position;

Fig. 5 is a similar view illustrating the rotatable member of the servo-motor in another of its positions;

Fig. 6 is a plan view of a sleeve member which is fixed upon the crank shaft of the engine;

Fig. 7 is view in side elevation of the ec-

centric for controlling the motion of the automatic cut-off valve;

Fig. 8 is a plan view of the eccentric;

Fig. 9 is a horizontal sectional view through the rotatable member of the servo- 60 motor;

Fig. 10 is a vertical sectional view taken substantially on the line 10—10 of Fig. 11, looking in the direction indicated by the arrow;

Fig. 11 is a sectional view taken substantially on the line 11—11 of Fig. 10;

Fig. 12 is a perspective view of one of the members shown in Fig. 11.

In Figs. 1 and 2 of the drawings, the valve gear embodying the present invention is illustrated as applied to the engine of a steam tractor and inasmuch as the tractor itself constitutes no part of the present invention, it will not be specifically described. Of the 70 engine of the tractor, however, the cylinder is indicated in general by the numeral 1, the piston working therein by the numeral 2, the valve chest by the numeral 3, the main valve by the numeral 4, and the automatic 75 cut-off valve by the numeral 5, the said valves 4 and 5 being of the ordinary cylindrical construction and the latter sliding within the former as usual. The main valve 4 reciprocates in the usual cylindrical chamber 6 within the valve chest, and ports 7 lead from this chamber to the opposite ends of the cylinder 1 for conducting the live steam to the ends of the said cylinder.

The numeral 8 indicates the crank shaft 90 which is driven from the engine through reciprocation of the piston 2, and fixed upon one end of this shaft is the usual crank disk 9 to the wrist pin of which is connected the usual connecting rod 10 which extends to 95 the rod of the piston 2. As ordinarily, the shaft 8 carries a combined fly wheel and pulley 11 from which power may be taken in driving threshers and other farm machinery, and any suitable and conventional train of gearing 12 transmits power from the shaft 8 to the traction wheels of the tractor. The numeral 13 indicates a tubular valve stem which is secured to one end of the main valve 4 and works through a 100 stuffing box 14 upon one end of the steam chest 3, and working in this tubular valve stem is the stem 15 for the automatic cut-off valve 5, this latter stem being preferably ex-

105 tended to work through a stuffing box 16 at 110

that end of the steam chest opposite the end at which the box 14 is located. The operative connection between the mechanism embodying the present invention and the valve 5 stems 13 and 15 will presently be specifically described.

Briefly described, the mechanism of the present invention includes a servo-motor device which is arranged upon the shaft 8 10 of the engine and through the operation of which eccentrics for imparting motion to the main and automatic cut-off valves may be reversed so as to reverse the engine, manually operable valve means being provided for controlling the supply of steam 15 to the servo-motor for the purpose of adjusting the eccentrics. The servo-motor and eccentrics above referred to are not mounted directly upon the shaft 8 but upon a sleeve which is fitted to and rotatable with 20 the shaft. This sleeve is indicated in general by the numeral 17 and the same is connected for rotation with the shaft by a key or other suitable device indicated by 25 the numeral 18. Throughout the major portion of its length or more specifically throughout that portion of its length upon which the servo-motor is mounted, the sleeve is of uniform diameter but throughout 30 the remainder of its length is reduced in diameter as indicated by the numeral 19, this latter portion of the sleeve supporting the eccentrics. The servo-motor is indicated in general by the numeral 20 and includes a rotor 21 best shown in Figs. 3^a, 4, 35 5 and 11 of the drawings. This rotor comprises a cylindrical body which is formed axially with an opening 22 of a diameter to rotatably fit the sleeve 17 and the said body is formed with a steam chamber 40 23 which opens through one lateral face of the body, this face of the body being, however, covered by a copper plate or head 24 bolted or otherwise secured in place as indicated by the numeral 25 so as to close the steam chest 23. A packing ring 26 is seated 45 in a circumscribing groove 27 formed in the sleeve 17 and in a companion groove 28 formed in the inner face of the plate 24 and surrounding the opening in the plate which 50 is provided to accommodate the sleeve 17. This packing ring serves, of course, to prevent leakage of steam from the steam chamber 23 of the rotor. The steam chamber 23 of the rotor is substantially of segmental form, the outer arcuate wall thereof being indicated by the numeral 29, and the end walls one by the numeral 30 and the other by the numeral 31. For a purpose to 55 be presently explained, the end walls 30 and 31 are provided with shoulder portions indicated by the numerals 32 and 33 respectively. Also for a purpose to be presently explained, the wall of the opening 22 in the rotor is formed with a circumferen-

tially extending passage 34 which passage extends between the inner ends of the end walls 30 and 31 of the steam chamber 23 and communicates with the said chamber. The closed side of the rotor constitutes one 70 side wall of this passage, and as the passage does not open through that face of the rotor through which the steam chamber 23 opens, the said passage is closed except at its ends. A packing element 35 is mounted in 75 the rotor 21 and extends into the passage 34, so as to position a steam-tight partition wall within the passage. As illustrated in Figs. 4 and 5, the packing 35 is pressed into steam tight engagement with the sleeve 17 by 80 means of a longitudinally curved leaf spring 35'. The piston of the servo-motor is in the nature of a relatively thick blade or head 36 which is integral with or secured to the outer surface of the sleeve 17 85 and projects radially therefrom and into the steam chamber 23 of the rotor, this piston blade or head being of a width and radial length substantially corresponding to the width and breadth of the said chamber 90 23. In order, however, to insure of a steam-tight fit between the piston head 36 and the walls of the chamber 23, the side and outer edges of the head 36 are formed with 95 grooves 37 which receive packing strips 38 normally held projected by leaf springs 39 operating against the inner edges of the packing strips and against the inner walls of the grooves. The piston head 36, of course, rotates with the shaft 8 inasmuch 100 as it is carried by the sleeve 17 which is fixed upon the shaft, but it will be understood that when live steam is admitted to the chamber 23 at one side or the other of the piston head 36, the rotor 20 will be 105 rotated upon the sleeve 17 in the direction from which steam is admitted. Thus if the piston head 36 is in the position shown in Fig. 5 of the drawings as also the rotor 20, in which position the shoulder 33 will 110 abut against one side of the piston head 36 and steam is admitted into the space between the said face or side of the piston head and the end wall 31 of the steam chamber, the rotor will be rotated to the right 115 in the said figure and upon the sleeve 17 notwithstanding the fact that it also rotates with the sleeve. On the other hand, should the shoulder 32 be in engagement with the opposite face of the piston head 120 and should steam be admitted into the space between the said face of the piston head and the end wall 30 of the steam chamber, the rotor would be rotated toward the left or in the reverse direction to that 125 mentioned above and until the shoulder 33 had come into position against the said piston head. In order that steam may be admitted to either side of the piston 36, the sleeve 17 is formed with longitudinally ex- 130

tending steam passages 40 and 41 and with ports 42 and 43 which establish communication between the ports 40 and 41 respectively, and the steam chest at opposite sides 5 of the piston 36, the port 42 opening into that end of the steam chest having the end wall 31 and the port 43 opening into that end of the steam chest or chamber having the wall 30. In addition to the ports 42 and 10 43, the sleeve 17 is formed through its exterior with other ports 44 and 45 which communicate respectively with the passages 40 and 41.

Associated with the rotor of the servomotor is a steam chest through which steam is supplied to the steam chamber 23 of the rotor and this chest is indicated in general by the numeral 46 and is in the nature of a two section substantially cylindrical body 15 which is disposed to fit about the sleeve 17 as clearly shown in Figs. 3^a and 11 of the drawings, and which is provided interiorly with circumferential steam passages 47 and 48 which are in communication respectively 20 with the ports 44 and 45. The chest 46 is further formed interiorly with circumferential grooves 49, 50 and 51 receiving packing rings indicated respectively by the numerals 52, 53 and 54 these rings seating in 25 companion grooves 55, 56 and 57 formed exteriorly in the sleeve 17. The packing rings serve to prevent escape of steam from one to the other of the passages 47 and 48 and the escape of steam from either passage to 30 the exterior of the chest. One end of the chest 46 abuts against the closure plate or head 24 for the rotor and the chest is held in its position through the medium of the packing rings. The numerals 58 and 59 indicate 35 steam conducting pipes which are fitted at their ends into one side of the chest 46 and communicate, respectively, with the steam 40 passages 47 and 48.

Before proceeding to a description of the eccentric for controlling the motion of the main and automatic cut-off valves, and the manner in which these eccentrics are shifted, I will first describe the manually operable valve for controlling the supply of steam 45 to the steam chest of the servo-motor. This valve is clearly illustrated in Fig. 3 of the drawings and is indicated in general by the numeral 60, being mounted upon the tractor at a point near the operator's position, as 50 clearly shown in Fig. 1 of the drawings. The casing for the valve is indicated by the numeral 61 and live steam is to be supplied to the casing by a steam pipe 62 which leads from the steam dome of the boiler and which 55 pipe may be provided with any suitable manually operable cut-off valve 63. The pipe 62 communicates with the upper side of the valve casing 61 intermediate the ends thereof, and exhaust ports 64 and 65 lead from the 60 valve casing at the under side thereof and at

the ends of the said casing. The valve casing 61 is interiorly cylindrical and the same is formed with steam passages 66 and 67 which communicate with the pipes 58 and 59 respectively, these pipes being fitted at their 65 ends opposite their ends which communicate with the steam chest 46, through stuffing boxes 68 and 69 respectively, which boxes are located at one end of the valve casing 61. The said ends of the pipes 58 and 59 are fitted 70 through the stuffing boxes in a steam tight manner but yet may have movement through the boxes to accommodate for expansion and contraction and for stress imposed through the operation of the tractor. In order to 75 relatively brace the chest 46 of the servomotor and the casing 61 of the valve 60, a rod 70 is secured at one end in the side of the chest 46 and at its other end in the above mentioned end of the valve casing 61. This rod 80 75 and the pipes 58 and 59 serve also as a means for holding the steam chest 46 against rotation with or upon the sleeve 17. A cylindrical bushing or liner 71 is fitted into the valve casing 61 and abuts at one end against 85 that end of the casing through which the pipes 58 and 59 enter and which end of the casing is closed except for the communication of the pipes with the passages 66 and 67. The other end of the bushing or liner is engaged by a head 72 which is secured to and 90 closes the other end of the valve casing 61. In its ends, the bushing is formed with exhaust passages 73 and 74 which communicate with exhaust steam passages indicated 95 respectively by the numerals 75 and 76. The said bushing is also formed between its ends with ports 77 and 78 which respectively establish communication between the passages 66 and 67 and the interior of the bushing. 100 The valve proper is of the piston type and comprises the usual body 79 provided at its ends with heads 80 and 81 which are provided with suitable packing rings 82 and 83 fitting within the bushing 71 in a steam-tight 110 manner, the body 79 throughout its intermediate portion being reduced in diameter so as to provide a steam passage 84 about the valve. The stem of the valve is indicated by the numeral 85 and the same is slidably 115 fitted through a stuffing box 86 upon the head 72 and is pivotally connected as at 87 with a hand lever 88 located in front of the operator's position upon the tractor where it may be conveniently adjusted in the operation of 120 the mechanism. In order that steam supplied to the valve casing may pass to the space 84 and consequently to the ports 77 and 78, the casing 61 is provided interiorly with a steam passage 89, and the bushing 71 is 125 formed with ports 90 establishing communication between the said passage 89 and the said space 84.

Upon swinging the lever 88 to the left in Fig. 3 or, in other words, in a rearward 130

direction, the valve 79 will be moved to such position that the head 80 will lie between the ports 77 and 90 and live steam will then be supplied from the passage 89, through the 5 ports 90 and into the space 84 from whence it will issue into the ports 78 and passage 67, pipe 59, port 45, passage 41 and port 43 to the steam chamber of the rotor of the servo-motor where, acting against the piston 10 36 and the end wall 30 of the said steam chamber, it will serve to rotate the rotor of the servo-motor in a counter clockwise direction as shown in Fig. 5 of the drawings. The steam at the opposite side of the piston 15 36 will exhaust through the port 42, passage 40, port 44, pipe 58, passage 66, ports 77, and exhaust ports 64. On the other hand, when the lever 88 is swung forwardly or, in other words, toward the right in Fig. 3 of 20 the drawings, the valve 79 will be shifted so that its head 81 will lie between the ports 78 and the ports 90 and in such position of the parts, live steam will pass from the passage 89 through the ports 90, into the annular passage 84, through the ports 77, passage 66, pipe 58, port 44, passage 40, and port 42 to the forward or right hand side of the piston in Fig. 3^a of the drawings where, 25 acting against the piston and the end wall 31 of the steam chamber of the rotor, it will cause rotation of the rotor in a clockwise direction or, in other words, toward the right in Fig. 5 until the shoulder portion 32 comes into engagement with the rear face of 30 the piston 36. At such time, steam will exhaust from the said steam chamber of the rotor at the other side of the piston, through the port 43, passage 41, port 45, pipe 59, passage 67, ports 78, and exhaust port 65 to 35 the atmosphere. From the foregoing it will be seen that by a simple shifting of the lever 88, the rotor of the servo-motor may be rotated in a forward or rearward direction about the sleeve 17 while at the same time it 40 is rotating with the said sleeve. By the provision of the passage 34 in the rotor of the servo-motor and the provision of the packing element 35, the steam pressure within the steam chamber is balanced at the 45 opposite sides of the piston and more particularly, the pressure of steam against the wall 29 and the opposing surface of the sleeve 17 will not bind the wall of the opening 22 against the sleeve in a manner to interfere with free rotary adjustment of the 50 rotor about the sleeve.

The eccentric for imparting motion to the main valve 4 is indicated in general by the numeral 91 and has an eccentrically positioned opening 92 axially alined with the opening 22 of the rotor of the servo-motor and of a diameter to snugly and yet rotatably fit the reduced portion 19 of the sleeve 17, the said eccentric being integral with 55 that face of the rotor 20 opposite the face

to which the closure plate 24 is applied. A packing ring 93 is fitted in a groove formed in the said reduced portion of the sleeve 17 and serves to prevent escape of steam. For a purpose to be presently explained, the 70 outer face of the eccentric 91 is formed with an arcuate slot 94 concentric to the axis of the shaft 8 and to the opening 92. Fitted to the eccentric 91 is an eccentric strap indicated by the numeral 95, and a radius rod 96 75 extends from the strap 95 and is pivotally connected at its forward end to the outer end of the tubular valve stem 13 for the main valve 4. The main valve eccentric 91, of course, rotates with the rotor of the servo-motor which in turn is driven through the rotation of the shaft 8 so that reciprocatory motion is imparted to the main valve 4. However, when the rotor of the servo-motor is rotatably adjusted upon the sleeve 85 through manipulation of the controlling lever 88, the said eccentric will be correspondingly rotatably adjusted so as to reverse the motion of the main valve.

The automatic cut-off valve eccentric is 90 indicated in general by the numeral 98 and is provided with an eccentrically located opening 99 to receive the reduced portion of the sleeve 19, this eccentric being rotatable upon the said sleeve and being positioned beside the outer face of the eccentric 91. For a purpose to be presently explained, that face of the eccentric 98 which is presented toward the outer face of the eccentric 91 is formed with a laterally projecting 95 stud 100 which works in the slot 94. The opposite or outer face of the eccentric 98 is formed with an arcuate slot 101. To establish driving connection between the shaft 8 and the eccentric 98, there is provided a 100 driving member which is clearly shown in Fig. 12 of the drawings and indicated in general by the numeral 102, this member comprising a ring 103 disposed to fit the shaft 8 at the reduced end of the sleeve 17 105 and provided upon its face which opposes the end of the sleeve with segmental lugs or bosses 104 which are fitted into correspondingly formed recesses 105 formed in the end of the sleeve 17, securing screws or 110 bolts 106 being fitted through the ring 103 between the ends of the bosses 104 and into the said end of the said sleeve. The ring is provided with a peripheral ear 107 and this ear supports a laterally projecting stud 108 115 which works in the slot 101. The slot 94 extends through approximately 72° and the slot 101 extends through approximately 38°. the relation of these slots in one position of the eccentrics being shown clearly in Fig. 125 10 of the drawings and this figure illustrating also in broken lines another extreme position of adjustment of the eccentrics. Assuming that the rotor of the servo-motor and the piston of this motor occupy the 130

relative positions shown in Fig. 5 of the drawings in which position the piston 36 is in driving engagement with the shoulder portion 33 of the wall 31 of the steam chamber 23 of the rotor, and further assuming that the stud 100 is in engagement with one end of the slot 94 and the stud 108 is in engagement in one end of the slot 101, motion will, of course, be transmitted from the 5 shaft to the rotor through the piston 36 as well as from the shaft, through the stud 108 to the automatic cut-off valve eccentric 98 and through the pin 100 upon this eccentric to the main valve eccentric 91 and consequently to the rotor 20. Thus the rotor of the servo-motor rotates with the sleeve 17 as also the eccentrics 91 and 98 imparting reciprocatory motion to the main and automatic cut-off valves. In order to reverse the 10 motion of these valves, the lever 88 is to be adjusted so as to admit steam into the space between the piston 36 and the wall 31 of the steam chamber 23 of the rotor 20 whereupon the said rotor 20 will be rotatably adjusted 15 about the sleeve 17 carrying with it the main valve eccentric 91. In this rotation of the main valve eccentric with relation to the sleeve 17 and, consequently, to the shaft 8, the main valve will have its motion 20 reversed. The rotor 20 in its rotative movement about the sleeve 17 moves through substantially 110° and, consequently, the opposite end wall of the slot 94 will first be brought into engagement with the stud 100 25 when the eccentric 91 has moved through substantially 72° and upon further motion the stud 100 will be carried with the main eccentric 91, thus picking up and rotating the automatic cut-off eccentric 98 through 30 substantially 38° which will bring the opposite end of the slot 101 into engagement with the stud 108 upon the driving member 102. Of course, the rotative adjustment of 35 the eccentric 98 will reverse the motion of the automatic cut-off valve.

An eccentric strap 109 is fitted to the eccentric 98 and a short rod 110 extends from this strap and is pivotally connected as at 111 with a link 112 which is pivotally 40 mounted at its lower end as at 113 and which corresponds to the link of the ordinary valve gear. The usual link block 114 works in the link 112 and connected to this block is a radius rod 115 which rod extends to and 45 is pivotally connected as at 116 with the stem 15 of the automatic cut-off valve 5. The motion of the automatic cut-off valve eccentric 98, of course, imparts oscillatory motion to the link 112 and when the link 60 block 114 is in the upper portion of the link, the automatic cut-off valve will have full travel, but the length of stroke of this valve will be shortened as the block 114 moves downwardly in the link. In order to automatically 65 adjust the block in the link in

accordance with variations in load, a governor device is provided which may be of any conventional type so long as it is adapted to act upon the radius rod 115 to automatically raise and lower this rod in accordance with variations in the speed of rotation of the governor. The governor illustrated in the drawings is of centrifugal ball type and is indicated in general by the numeral 117, the stem of the governor being 70 indicated by the numeral 118, the balls by the numeral 119, and the sleeve which is 75 slidable upon the stem by the numeral 120. A bracket 121 extends from a fixed part of the governor and mounted for rocking 80 movement upon this bracket is a lever 122 provided at one end with a ball weight 123 and having pivotally connected to its other end as at 124, the upper end of a link 125 which link at its lower end is pivotally 85 connected as at 126 with the radius rod 115. Of course, as the sleeve 120 is moved upwardly through the outward movement of the balls 119 when the governor is running 90 at high speed, the lever 122 will be rocked 95 so as to move the link 125 downwardly and thereby move the link block 114 downwardly in the link so as to shorten the stroke of the automatic cut-off valve. On the other hand, when the load is increased and the 100 governor balls 119 move inwardly thus permitting lowering of the sleeve 120 through the medium of the usual spring employed upon the governor stem, the link 125 will be pulled upwardly and the link block 114 will be moved upwardly in the link 112 thus 105 increasing the length of stroke of the automatic cut-off valve. Motion is imparted to the governor by means of a bevel gear 127 fixed upon the shaft 8 and meshing with a beveled gear 128 fixed upon a shaft 129 which is journaled in the frame of the governor and carries a friction wheel 130 with which 110 co-operates a friction wheel 131 mounted upon a shaft 132 within the frame 110 of the governor and suitably geared with the governor stem. The friction wheel 131 is slidably but non-rotatably mounted upon the shaft 132 so that rotary motion is transmitted from the shaft 129 to the cross shaft 115 132 through contact of the disk 130 and the wheel 131. The wheel 131 is movable across the face of the wheel 130 so that the governor may be set for any desired speed. 120 As illustrated in Figs. 1 and 2, the ratio between the disk 130 and the wheel 131 may be varied through the medium of a manually operable shaft 133 having its forward end provided with a worm 134 meshing with the gear 134' of a sleeve 135. The sleeve 135 is threaded through a collar 136 carried by the governor frame and connected to the wheel 132 so that the wheel 125 may be moved across the face of the disk 130 by rotation of the shaft 133. The rear 130

end portion of the shaft 133 is rotatably supported by a bracket 137 secured to one side of the valve case 60 and is provided with an operating wheel 138 arranged adjacent the various other operating devices for the tractor.

When it is desired to set the governor to act at a high speed of the tractor, the wheel 131 may be moved inwardly toward the center of the disk 130 so as to decrease the speed of the shaft 132 in proportion to the speed of the crank shaft. By thus decreasing the speed of the shaft 132 as compared with the speed of the crank shaft 8, the operation of the governor is somewhat retarded. More specifically, it is necessary for the crank shaft to attain a much greater speed when the friction disk 130 and the wheel 131 are so adjusted in order to cause the governor to operate. On the other hand, if it is desired to set the governor to act during a slow speed of the tractor, the wheel is moved outwardly toward the periphery of the disk 130 whereby the speed of the governor shaft 132 is increased as compared with the speed of the crank shaft 8. In this manner the number of revolutions per minute made by the governor is appreciably increased as compared with the number of revolutions made by the crank shaft 8 and therefore the governor will act at a much slower speed.

In this manner the operator of the tractor may manually set the governor to act at any speed without the necessity of leaving his seat, or the other operating devices of the tractor. It is obvious also that the governor is capable of various intermediate adjustments.

Having thus described the invention, what is claimed as new is:

1. In reversing mechanism of the class described, a steam engine shaft, main- and cut-off-valve eccentrics mounted thereon and rotatably shiftable, a servo-motor including a rotor carried by the shaft and rotatably shiftable thereon, means for effecting adjustment of the eccentrics upon the rotative adjustment of the rotor, and means for controlling the servo-motor.

2. In reversing mechanism of the class described, a steam engine shaft, main- and cut-off-valve eccentrics mounted thereon and rotatably shiftable, a servo-motor including a rotor carried by the shaft and rotatably shiftable thereon, one of said eccentrics being movable with the rotor, means for effecting adjustment of the other eccentric upon rotative adjustment of the rotor, and means for controlling the servo-motor.

3. In reversing mechanism of the class described, a steam engine shaft, main- and cut-off-valve eccentrics mounted thereon and rotatably shiftable, and a servo-motor including a rotor carried by the shaft and ro-

tatably shiftable thereon, the main valve eccentric being rotatable with the rotor, means for effecting adjustment of the cut-off-valve eccentric upon rotative adjustment of the main valve eccentric, and means for controlling the servo-motor.

4. In reversing mechanism of the class described, a steam engine shaft, main- and cut-off-valve eccentrics mounted thereon and rotatably shiftable, a servo-motor including a rotor carried by the shaft and rotatably shiftable thereon and having a steam chamber, a piston fixed with relation to the shaft and extending into the said steam chamber, means for selectively supplying steam to the steam chamber at either side of the piston, and means for effecting adjustment of the eccentrics upon rotative adjustment of the rotor.

5. In reversing mechanism of the class described, a steam engine shaft, main- and cut-off-valve eccentrics mounted thereon and rotatably adjustable, a servo-motor including a rotor carried by the shaft and rotatably shiftable thereon and having a steam chamber, a piston fixed with relation to the shaft and extending into the said steam chamber, means for selectively supplying steam to the steam chamber at either side of the piston, one of the eccentrics being rotatable with the rotor, and means for effecting adjustment of the other eccentric upon rotative adjustment of the rotor.

6. In reversing mechanism of the class described, a steam engine shaft, main- and cut-off-valve eccentrics mounted thereon and rotatably shiftable, a servo-motor including a rotor rotatable with the shaft and rotatably shiftable with respect thereto, means for effecting adjustment of the eccentrics upon rotative adjustment of the rotor, and means for controlling the servo-motor.

7. In reversing mechanism of the class described, a steam engine shaft, main- and cut-off-valve eccentrics mounted thereon and rotatably shiftable, a servo-motor including a rotor rotatable with the shaft and rotatably shiftable with relation thereto, the rotor having a steam chamber, a piston fixed with relation to the shaft and extending into the steam chamber of the rotor, means for effecting adjustment of the eccentrics upon rotative adjustment of the rotor, a steam chest upon the shaft having communication with the steam chamber of the rotor at opposite sides of the piston, and means for controlling the supply of steam to and exhaust of steam from the said steam chest.

8. In reversing mechanism of the class described, a steam engine shaft, main- and cut-off-valve eccentrics mounted thereon and rotatably shiftable, a servo-motor including a rotor rotatable with the shaft and rotatably shiftable with relation thereto, one of the eccentrics being rotatable with the ro-

tor, coating means upon the said eccentric and the other eccentric for rotatably adjustably shifting the latter upon adjustment of the former, and means for controlling the servo-motor.

9. In reversing mechanism of the class described, a steam engine shaft, main- and cut-off-valve eccentrics mounted thereon and rotatably shiftable, a servo-motor including a 10 rotor rotatable with the shaft and rotatably shiftable with relation thereto, the rotor having a steam chamber, a piston fixed with relation to the shaft and extending into the steam chamber, means for selectively admitting 15 fluid under pressure to the steam chamber at opposite sides of the piston therein, the said chamber having a circumferential length less than the entire circumference of the rotor, the rotor having a steam passage 20 in communication with said steam chamber, a packing extending into the steam passage, and means for effecting adjustment of the eccentrics upon rotative adjustment of the rotor.
10. In reversing mechanism of the class described, a steam engine shaft, a sleeve mounted thereon and rotatable therewith, main- and cut-off-valve eccentrics mounted upon the sleeve and rotatably shiftable, a 25 servo-motor including a rotor mounted upon the sleeve and rotatable therewith and rotatably shiftable thereon, means for effecting adjustment of the eccentrics upon rotative adjustment of the rotor, a steam chest upon 30 the sleeve having steam passages, the rotor having a steam chamber, a piston extending from the sleeve and into the said steam chamber of the rotor, the sleeve having steam passages establishing communication between the steam chest and the steam chamber.

ber of the rotor at opposite sides of the piston, steam conducting pipes communicating with the steam chest, and a manually adjustable valve for controlling the supply of steam to and the exhaust of steam from 45 the said pipes.

11. The combination with a steam engine shaft, of main and cut-off valve eccentrics mounted thereon, a rotor rigidly connected to said main valve eccentric and having a 50 segmental chamber, a piston connected to said shaft and arranged in said segmental chamber, and means for admitting fluid pressure to said segmental chamber on either side of said piston for rotatably adjusting 55 said rotor and said main and cut-off valve eccentrics, said cut-off valve eccentric being connected to said main valve eccentric and adjustable with relation to the same.

12. The combination with a steam engine 60 shaft, of a sleeve secured thereon and having longitudinally extending passages provided with ports, main and cut-off valve eccentrics mounted on said sleeve, a rotor rotatably arranged on said sleeve and having a 65 segmental chamber in communication with said ports, said rotor being rigidly connected to said main valve eccentric, a piston connected to said sleeve and arranged in said chamber between said ports, a valve 70 chest surrounding said sleeve and having means for supplying steam through said passages to said chamber on either side of said piston whereby either end wall of said chamber may be engaged with said piston 75 for shifting said main and cut-off valve eccentrics.

In testimony whereof I affix my signature.

EARNEST P. WELCH. [L.S.]
